CLAIM

The ornamental design for a retracting extension cord,
as shown and described.

DESCRIPTION

FIG. 1 is a front elevational view of a retracting extension cord showing my new design;

FIG. 2 is a rear elevational view thereof;

FIG. 3 is a left side elevational view thereof;

FIG. 4 is a right side elevational view thereof;

FIG. 5 is a top plan view thereof;

FIG. 6 is a bottom plan view thereof; and,

FIG. 7 is a front and upper right perspective view
thereof shown on an enlarged scale.
